UNITED STATES PATENT OFFICE.

ALBERT A. CALLOCOTTE, OF NORTH YAKIMA, WASHINGTON.

AIRSHIP.

1,092,973.

Specification of Letters Patent. Patented Apr. 14, 1914.

Application filed April 22, 1913. Serial No. 762,894.

To all whom it may concern:

Be it known that I, ALBERT A. CALLOCOTTE, a citizen of the United States, residing at North Yakima, in the county of Yakima 5 and State of Washington, have invented a new and useful Airship, of which the following is a specification.

This invention relates to air ships of the lighter than air type, one of its objects being to provide a gas container having horizontally and vertically extending tubes in which are arranged means for propelling the air ship forwardly and rearwardly as well as for controlling the upward movement 15 of the structure.

A further object is to provide a gas container which is connected directly to the car of the air ship and which is so shaped and proportioned as to act as a parachute for retarding the downward movement of the air ship.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 25 the scope of what is claimed, without departing from the spirit of the invention.

In the accompanying drawings the preferred form of the invention has been shown.

In said drawings:—Figure 1 is a perspective view of the air ship. Fig. 2 is a bottom plan view thereof.

Referring to the figures by characters of reference 1 designates a gas container having opposed upper and lower conical portions meeting at their peripheries to form the margin of the container. Extending axially through this container is a normally vertical tube 2, this tube extending downwardly below the container and through the center of a circular car 3. This car is provided with suitably arranged supporting wheels 4 and extending forwardly and rearwardly from the car are rudders 5 and 6 respectively whereby the air ship can be 50 steered while in flight.

Extending through the side portions of the gas container and below the margin 7 thereof are tubes 8, these tubes being parallel and being located at equal distances 55 from the center, the longitudinal axes of the tubes being parallel with a line running from

the center of the front of the air ship to the center of the back thereof.

Any suitable motor such as shown at 9 may be mounted in the car, suitable mechanism, not shown, being provided whereby motion is transmitted from this motor to propellers 10 located in the horizontal tubes 8 and to another propeller 11 located in the vertical tube 2.

It will be apparent that the container 1, which extends a considerable distance beyond the periphery of the car 3, will hold sufficient gas to elevate the entire structure. The speed of elevation can be controlled by 70 rotating propeller 11 so as to displace air upwardly within the tube 2 and thus tend to force the air ship downwardly. The air ship is propelled forwardly or rearwardly by rotating the propellers 10, thus setting 75 up currents of air within the horizontal tubes 8. It will be noted that the bottom of the container 1 rests on and is secured directly to the top of the car 3 and thus the tube 2 extends not only through the container but also through the center of the car. This tube thus constitutes a reinforcing central post about which the air ship is constructed. Should the gas within the container leak therefrom and thus fail to sustain the air ship, or should the air ship begin to descend from any other cause, the large container 1 will act as a parachute to retard the downward movement so that a landing can be effected without danger to 80 the occupants of the car.

Importance is attached to the fact that the container as well as the car is circular. Thus the resistance offered to air currents from all directions is the same and there is no danger of the container buckling under the pressure of the currents. Furthermore it thus becomes possible to more quickly turn the air ship and to more readily steer it while in flight than is possible where the ordinary 100 cigar-shaped container is employed.

While the propeller 11 is especially designed to force the airship downwardly as hereinbefore set forth, it is to be understood that by rotating the propeller in the opposite direction, it will assist in elevating the machine should there be a scarcity of gas in the container.

The container 1 is preferably held extended by a circular frame 12 mounted 110 therein and guys, such as indicated at 13 in Fig. 1, may be extended downwardly from

this frame to the car 3. Thus it will be seen that, should the container collapse, the upper portion thereof will act as a parachute while the lower portion will buckle inwardly.

What is claimed is:—

1. An air ship including a tubular post, a car connected thereto, a gas container secured about the post and fastened at its bottom upon the car, horizontally extending parallel tubes within the side portions of the gas container and close to the car, and propellers mounted for rotation within the tubes.
- 15 2. An air ship including a circular car, a tubular post extending upwardly from the center thereof, a circular gas container of greater diameter than the car and formed of oppositely disposed upper and lower substantially conical portions connected together at their margins, said container being secured about the post and being fastened at its bottom upon the car, horizontally extending parallel tubes within the side portions of the gas container and close to the car, propellers mounted for rotation within the tubes, and a propeller mounted for rotation within the post.

side portions of the gas container and close to the car, and propellers mounted for rotation within the tubes.

3. An air ship including a circular car, a tubular post extending upwardly from the center thereof, a circular gas container of greater diameter than the car and formed of oppositely disposed upper and lower substantially conical portions connected together at their margins, said container being secured about the post and being fastened at its bottom upon the car, horizontally extending parallel tubes within the side portions of the gas container and close to the car, propellers mounted for rotation within the tubes, and a propeller mounted for rotation within the post.

In testimony that I claim the foregoing as my own, I have hereto affixed my signature in the presence of two witnesses.

ALBERT A. CALLOCOTTE.
